(57) **CLAIM**

The ornamental design for a bottle, as shown and described.

DESCRIPTION

FIG. 1 is a top, front, left side perspective view of a bottle embodying our new design;

FIG. 2 is a front elevational view thereof, the rear elevational view being a mirror image thereof except for the unclaimed thread;

FIG. 3 is a right side elevational view thereof, the left side elevational view being a mirror image thereof except for the unclaimed thread;

FIG. 4 is a top plan view thereof; and,

FIG. 5 is a bottom plan view thereof.

The broken lines shown of the pour spout and on the bottom surface of the claimed design are included for the purpose of illustrating environmental structure and form no part of the claimed design.

1 Claim, 4 Drawing Sheets

FIG. 1

FIG. 2

FIG. 3

FIG. 4

FIG. 5
